DESIGN FOR A REFRIGERATOR

Ella A. Vickerman, Pittsburgh, Pa.

Application January 12, 1935, Serial No. 54,823

Term of patent 7 years

To all whom it may concern:

Be it known that I, Ella A. Vickerman, a citizen of the United States, residing at Pittsburgh, in the county of Allegheny and State of Pennsylvania, have invented a new, original, and ornamental Design for a Refrigerator, of which the following is a specification, reference being had to the accompanying drawing, forming part thereof.

Figure 1 is a front elevational view of the refrigerator.

Figure 2 is a side elevational view of Figure 1. Figure 3 is a top plan view of Figures 1 and 2. Figure 4 is a perspective view of a refrigerator showing my design, on a reduced scale.

The dominant feature of the design consists in the ornamentation of the upper portion thereof shown in Figures 1 and 4.

I claim:

The ornamental design for a refrigerator, as shown and described.

ELLA A. VICKERMAN.
